United States Patent Office

Des. 190,958
Patented July 25, 1961

190,958

CABINET OR SIMILAR ARTICLE

Texine Lee Britt, 1506 N. Road St., Elizabeth City, N.C.

Filed Nov. 6, 1958, Ser. No. 53,280

Term of patent 14 years

(Cl. D33—19)

Fig. 1

Fig. 2

The side not shown is like the side shown while back of the cabinet is plain and unornamented.

I claim:

The ornamental design for a cabinet or similar article, as shown and described.
